WILLIAM HAINSWORTH, OF SHARPSVILLE, PENNSYLVANIA.

Letters Patent No. 87,663, dated March 9, 1869.

IMPROVEMENT IN METHOD OF CONSTRUCTING MOULDS FOR METALLIC CASTINGS.

The Schedule referred to in these Letters Patent and making part of the same.

To all whom it may concern:

Be it known that I, WILLIAM HAINSWORTH, of Sharpsville, in the county of Mercer, and State of Pennsylvania, have invented a new and improved Machine for Making Moulds and Cores for Castings; and I do hereby declare that the following is a full, clear, and exact description of the construction and operation of the same, reference being had to the accompanying drawings, making a part of this specification, in which—

Figure 1 is a front elevation, and

Figure 2, a side elevation.

This invention consists in fastening the pattern in the flask, in proper position, and then, as the sand, is filled in, raising both pattern and flask together to a considerable height, and dropping them upon a solid bed, so that the concussion produced by the fall may pack the sand closely and evenly in the flask in and around the pattern.

In the drawings—

A is a solid bed, at the bottom of the pit in which the flask is to rise and fall;

B B is the frame-work, which supports the operating mechanism;

C is the flask; and

D, the pattern, the latter capable of firm attachment to the former in proper position for forming the mould, and also of being easily detached. The pattern is made hollow, and is in two semi-cylindrical pieces, properly connected together, forming, when shut, a tube, smooth both inside and outside.

The flask is larger at the bottom than at the top, and is provided with a trap-door at its lower end, which allows the sand to drop out when desired.

The pattern, D, extends up through guides B' B', that hold it in a vertical position, and allow it to rise and fall without turning on its vertical axis.

The essential feature of this invention consists in fastening the pattern and flask together by means of stays, straps, or hooks, and then, while the sand is filling into the flask, raising the two up by means of the upper end of the pattern, and letting them fall together upon the bed A, so as to firmly compact the sand.

To raise and drop the plunger D, I employ a tripping-wheel, T, provided with a tooth, t, which tooth strikes against a projection, e, on the plunger, and raises the latter with the flask until the projection e slips off from the tooth t, when the pattern and flask will fall together upon the bed A.

The same shaft M that carries the wheel T, also carries a spur-wheel, N, alongside of the wheel T, which wheel N may be made to engage with a rack, n, upon the plunger, and raise the latter out of the flask when required, the straps binding the two together having been first undone.

A fast pulley, F, and a loose one, L, may be attached to the shaft M, for the purpose of operating it conveniently.

Cores for moulds may be made in a similar manner, by raising core-box, core-bar, and sand together, and letting them all drop upon a hard bed.

Having thus described my invention,

What I claim as new, and desire to secure by Letters Patent, is—

The packing of sand, for a mould, in a flask, by raising the same, together with the pattern, and letting them all drop upon a hard bed, substantially as shown and described.

WILLIAM HAINSWORTH.
